UNITED STATES PATENT OFFICE.

RUDOLPH LIEBER AND CARL LAMBERT, OF DUSSELDORF, GERMANY.

SKYLIGHT.

SPECIFICATION forming part of Letters Patent No. 739,013, dated September 15, 1903.

Application filed August 2, 1902. Serial No. 118,110. (No model.)

To all whom it may concern:

Be it known that we, RUDOLPH LIEBER and CARL LAMBERT, both citizens of the German Empire, and residents of Dusseldorf, Germany, have invented certain new and useful Improvements in Skylights, of which the following is a specification.

This invention relates to a skylight or glass roof which is so constructed that the unequal expansion between the glass and the metal frame will not be apt to open the joints around the edges of the glass.

In the accompanying drawings, Figure 1 is a plan of portion of a skylight or glass roof embodying our invention and with the caps omitted. Fig. 2 is a longitudinal section on line A B, Fig. 1; Fig. 3, a cross-section on line C D, Fig. 1; Fig. 4, a cross-section on line E F, Fig. 1.

The panes *a* of the skylight or roof are provided with upwardly-projecting flanges *a'* along both ends. They are supported upon the base of an inverted T-rail *b*, that constitutes the frame and to which they are secured by putty *c* or similar material. The web of the frame, together with the flanges *a'*, are covered by a cap *d*, that projects over the flanges and is connected to the frame by bolt *d'*. Between the cap *d* and the upper pane *a* are interposed packing-strips *e*, which form tight joints between the cap and the pane. The two flanges *a'* of each pane diverge so

that the distance between them is greater on top than at the bottom, Fig. 1. In this way the flanges at the upper end of the lower pane will embrace the flanges at the lower end of the upper pane to form an overlap joint, both sets of flanges being covered by a common cap *d*, Fig. 4. As the flanges project upwardly, they prevent rain that may creep in underneath the cap from flowing around the edges of the panes. They serve, further, to lock the panes against displacement, owing to unequal expansion between the glass and the metal.

45
What we claim is—

A skylight provided with an upper pane having upwardly-extending flanges, a lower pane having upwardly-extending flanges that embrace the flanges of the upper pane at the joint, a T-shaped frame supporting the panes, a cap embracing the flanges of both the upper and lower panes at the joint, means for securing the cap to the frame, and a packing intermediate the cap and the upper pane, substantially as specified.
